UNITED STATES PATENT OFFICE.

FREDERICK A. CONRAD, OF CHICAGO, ILLINOIS, ASSIGNOR TO THE WIDNEY COMPANY,
A CORPORATION OF ILLINOIS.

DISPLAY BOARD AND CLIP.

Application filed May 2, 1921. Serial No. 466,100.

To all whom it may concern:

Be it known that I, FREDERICK A. CONRAD, a citizen of the United States, residing at Chicago, in the county of Cook and State 5 of Illinois, have invented certain new and useful Improvements in Display Boards and Clips, of which the following is a specification.

The invention relates to improvements in 10 display boards and an improved clip for holding washers, gaskets, strips, and the like, thereon.

One of the objects of the invention is to 15 provide a display board that may be made of multi-ply cardboard stock, such as building board, because it is inexpensive, and is sufficiently strong and durable, and because it is best adapted to receive and hold the especial clip which in cooperation therewith 20 may be secured in place by use of a single rivet and, furthermore, the relative thinness of the board permits the use of standard rivets that are cheap in price.

In the maintenance of automobiles, and 25 especially the engines associated therewith, a great variety of gaskets, washers, disks and strips, usually of felt, cork, etc., are required from time to time. It is convenient for the workman and salesman, and advisable 30 from an advertising standpoint, to have the supply of such devices mounted upon a display board from which they may quickly be taken as they are needed. It is necessary, however, to provide a holding means 35 or clip that will securely hold these devices in place until they are intentionally removed.

Display boards of this general character have heretofore been in use, but in such 40 boards the means for holding the gaskets, etc., in place have been of such character that they require too much time and trouble to remove the devices from the board or, on the other hand, in some boards the devices 45 have been so insecurely held in place that a passerby would frequently dislodge a number of them by mere contact therewith.

Another object of the invention is to provide a holding clip, of especial construction, which is not only most excellently well 50 adapted to hold gaskets, washers, etc., of a yielding nature, such as used on boards of this type and which has capacity to contain a number of them, but it affords the greatest convenience in loading the clips, and,

furthermore, it cooperates with the more or less yielding board, such as building board, as an auxiliary means to hold the clip in place and prevent it from being rotated about the single rivet used to hold it on the 60 board.

Furthermore, the means of fastening the clip to the board contributes as a means for preserving and maintaining its elasticity.

In the accompanying drawings,

Fig. 1 shows a board containing a number of clips holding washers, gaskets, strips, etc., thereon.

Fig. 2 shows a side elevation of the tempered steel clip ready to be attached to the 70 board.

Fig. 3 shows the changed form of the clip resulting from the manner of its attachment to the board showing several devices between its substantially parallel prongs.

Fig. 4 is an end elevation of the clip.

In all the views the same reference characters are used to designate similar parts.

The board 5 upon which the clips are mounted is preferably three ply building 80 board, more or less yielding on its face by application of some pressure.

The clips 6 when made and tempered are in shape when finished as they appear in Fig. 2 with the prongs 7 and 8 flaring outwardly, and with a hump 9 in the yoke that joins the prongs.

The hump 9 is perforated for a rivet 10. When the clip is to be applied to the board, a rivet is placed in the perforation of the 90 hump 9 and pressure is applied to set the rivet, at the same time the hump is thereby straightened out, or disappears, as shown in Fig. 3.

The curved portions or knees 11, where the yoke joins the prongs, sink into the contacting surface of the board. The sinking of these knees of the clip into the board prevents the clip from being rotated. Straightening the hump puts a tension on the rivet 100 and prevents the clip from becoming loose, and straightening the hump draws the prongs 7 and 8 into parallel positions to more intimately engage the parts 12 that are contained between them.

The prongs are bent in near their ends, at 105 13, to contact the distance between them at this point to more securely hold the fabrics therebetween when the clip is fully loaded and they are outturned at 14 to contribute 110

to the ease with which the clips can be loaded.

To quickly load a clip, as many of the gaskets, or the like, as the clip is to hold, are piled one upon another and the inner surface of the pile is brought into contact with the outwardly extending parts 14, then pressure is applied to the pile, whereupon the prongs will separate to admit the pile and 10 then spring back as shown in Fig. 3.

When a single laminae is required it is pulled outwardly, the clips will release it without disturbing the others contained therein.

15 Bending the knees 11 to draw the prongs 7 and 8 inwardly produces an elastic tension on the prongs without "setting" the

metal; consequently they retain their elasticity.

Having described my invention what I 20 claim as new and desire to secure by Letters Patent, is:—

A clip comprising two resilient outwardly extending prongs and a connecting yoke formed into an inturned hump, the main 25 body parts of the prongs being straight, the ends thereof each extending inwardly then outwardly into planes parallel with the main parts of the prongs and therebeyond whereby to engage and retain an object on the in- 30 side and on the outside of the clip.

In testimony whereof I hereunto subscribed my name.

FREDERICK A. CONRAD.
